Filed June 7, 1971, Ser. No. 150,890

Claims priority, application Switzerland Dec. 8, 1970

Term of patent 14 years

Int. Cl. D6—02

U.S. Cl. D6—31

FIG. 1

FIG. 2

FIG. 3

FIG. 4

FIG. 1 is a front view of my chair or similar article, incorporating my invention;

FIG. 2 is a side view of the chair or similar article depicted in FIG. 1; the opposite side being identical to the side shown;

FIG. 3 is a rear view of the chair or similar article depicted in FIG. 1; and

FIG. 4 is a perspective view of the chair or similar article depicted in FIG. 1.

The bottom surface of my chair or similar article, not shown is substantially flat.

I claim:

The ornamental design for a chair or similar article, as shown and described.
